REFRIGERATING APPARATUS

Ralph E. Baker, Detroit, Mich., assignor to Nash-Kelvinator Corporation, Detroit, Mich., a corporation of Maryland

Application June 11, 1937, Serial No. 147,750

10 Claims. (Cl. 62—116)

This invention relates to refrigerating apparatus and more particularly to the so-called household type of refrigerators.

One of the objects of my invention is to provide an improved refrigerator of the type wherein circulating air is refrigerated to the desired temperature for the proper preservation of foods and also ice cubes and the like are frozen, and to have provisions for periodically defrosting the cooling element which refrigerates the circulating air without in any manner disturbing the refrigerating effect of the system which is utilized for freezing purposes.

Another object of my invention is to provide an improved refrigerating system including two refrigerant evaporating elements which are so arranged within a refrigerator cabinet that the one element is used for ice making purposes and the other for cooling circulating air with the ice making element being isolated from the circulating air so as to avoid the possibility of extracting moisture from said circulating air, and to have provisions for temporarily discontinuing the refrigeration in the air cooling evaporator so that frost and ice may be melted therefrom while at the same time the ice making element remains effective to freeze ice cubes and the like and to retain same in a frozen condition while such defrosting of the air cooling element takes place.

Another object of my invention is to provide for varying the effectiveness of the aforesaid air cooling refrigerant evaporating element to compensate for any variations in the temperatures of the environment air surrounding the refrigerator to thus tend to maintain substantially constant temperatures in the food storage compartment of the refrigerator throughout variations and changes in temperatures of the environment air.

In the drawings:

Figure 1 is a fragmentary view of a refrigerator embodying features of my invention;

Figure 2 is a view shown partly diagrammatically and partly in cross section of a refrigerating apparatus embodying features of my invention;

Figure 3 is a view taken along the line 3—3 of Figure 2;

Figure 4 is a view taken along the line 4—4 of Figure 2;

Figure 5 is an enlarged fragmentary view of a portion of the refrigerator illustrated in Figure 1;

Figure 6 is an enlarged view shown in cross section of a valve mechanism used for controlling the flow of refrigerant in the apparatus shown in Figure 2;

Figure 7 is a fragmentary view of a modified form of refrigerating apparatus embodying features of my invention;

Figure 8 is a view in cross section of a modified form of the apparatus embodying features of my invention;

Figure 10 is a fragmentary view of a modified form of refrigerating apparatus embodying my invention.

It has always been a source of considerable inconvenience to users of household refrigerators and the like to periodically defrost the cooling unit of such refrigerators. The accumulation of ice or frost upon the outer surface of the cooling unit is occasioned by the design of and the temperature at which the unit operates. Moisture in the air circulating through the food compartment is condensed upon the surface of the cooling unit and freezes, forming a slowly increasing layer of ice which considerably reduces the efficiency of the cooling unit. In order to remove the frost thus accumulated it has been the practice to discontinue refrigeration to allow the cooling unit to warm up above the freezing point of water until it was again free of its coating of ice. In so doing, not only does the temperature of the food compartment rise but it is also no longer possible to obtain ice cubes or frozen desserts or to retain those already frozen. If, however, the temperature of the air cooling unit is controlled independently of the freezing unit wherein cubes and desserts are frozen, there is no longer any need for the freezing compartment to be inoperative since any frost collecting on the air cooling portion may be removed without interfering with the freezing portion of the unit in the freezing compartment.

In accordance with my invention I provide a refrigerator wherein ice cubes and the like may be continuously frozen and retained in a frozen condition even though the refrigerant evaporating element which cools the circulating air in the cabinet is being defrosted. This is accomplished by utilizing a heat absorber or cooling unit consisting of two refrigerant evaporators, one of which is used for freezing purposes and the other for cooling the circulating air in the food storage compartment of the cabinet. The two refrigerant evaporators are so connected that the one used for cooling circulating air may be defrosted without interfering with the refrigerating effect of the other or ice freezing evaporator. Thus the air cooling evaporator may be defrosted

25 general by the numeral 25. This cooling unit is 25
operatively associated with a refrigerant condensing element 26 which, for example, may be disposed within the aforesaid machine compartment in the lower part of the cabinet.

30 The cooling unit 25 comprises, in general, a thin sheet metal casing 27 positioned near the upper part of the compartment 24 and substantially midway between the two side walls of the cabinet 21. The casing 27 may be constructed 30
35 of any suitable material such as stainless steel or any other thin sheet metal and if desired may be provided with a coating of vitreous enamel such as porcelain on its inner and outer walls. The casing 27 is of box-like formation 40 and includes a front wall 28 provided with an opening 29 closed by a hinged door 30. Within the casing is disposed a heat absorber designated in general by the numeral 31, which is utilized for cooling circulating air within the compartment 24 and is also used for freezing ice cubes, 45 desserts and the like.

35 The heat absorber 31 of the refrigerating apparatus, shown to best advantage in Figures 2, 3 and 4, comprises in general, a tank 34 adapted to contain a quantity of liquid refrigerant and 50 refrigerant evaporators 36 and 40 which are in open communication with the tank by means of a common conduit 42 with the lower end of the tank 34. Evaporators 36 are two similar refrigerant expansion coils which have a juncture point 44 from which they extend upward along the sides of the casing 27 with which they are joined in good thermal contact, either through 55 welding or soldering. If desired, instead of coils 36, these two evaporators may simply form part of the casing 27 by using a double wall of sheet metal extending from top to bottom of the casing, refrigerant being contained in the space between the two walls. Evaporator 40 also extending upward from the juncture point 44 consists of shelves 46 joined by conduits 48. These shelves which are adapted to support ice pans are simply two sheets of metal welded or soldered together with sufficient space between to permit 60 liquid refrigerant to circulate therethrough. Evaporators 36 reunite at a valve 50 and when the valve 50 is open the evaporators are both in open communication with the top of the tank 34 through a conduit 52. Evaporator 40, on the 65 other hand, is always in open communication at 70

75 refrigerant from the cooling or evaporating elements through the vapor conduit 58, compresses 25 the gaseous refrigerant and delivers it to the condenser wherein it is liquefied and from which it is delivered to the float 61. Liquid refrigerant is delivered to the tank and various evaporators through the supply conduit 56. An automatic switch 78 is provided for controlling the operation of the motor preferably in response to changes in temperature in the tank 34 in the well known manner.

80 During periods when the float valve 64 is open, 35 liquid refrigerant passes through the conduit 56 whence it is injected into the inlet end of the conduit 42 by means of an injector or nozzle 80. Since the tank 34 is in open communication with the conduit 42 and normally with the upper ends of the evaporators 36 and 40, and conduit 42 is in open communication with lower ends of the same evaporators, the level of liquid refrigerant within the expansion conduits 36 and 40 will normally be substantially the same as in 45 the tank 34.

85 From the foregoing, it will be apparent that the large volume of liquid refrigerant in the tank will compel evaporated refrigerant in the expansion conduits to pass through the outlet 50 ends of same, namely 52 and 54, and into the tank due to the resistance offered by said large body of liquid. Under some circumstances, the evaporation of refrigerant will be so great in the expansion conduits 36 as to pick up liquid refrigerant and deliver it to the tank, whence 55 it descends to be recirculated.

90 In order to initiate the ebullition and to promote the circulation of liquid refrigerant through the expansion conduits 36 and 40, the injector has been provided. This prevents the super-heating of liquid refrigerant in the expansion conduits and tends to maintain uniform temperatures throughout the various parts of each 60 of the expansion conduits or evaporators. The injector is formed by tapering the outlet end 80 of the conduit 56. The tapered or restricted end 80 is disposed part way into a fitting 82 to which the conduit 42 is connected. The conduit 42 is secured to the tank, preferably by 70 welding. The injector is adapted to inject expanded refrigerant into the conduit 42. During periods when the float valve 64 is open, the refrigerant leaving the high pressure side of the system and entering the low pressure side 75

through the orificed valve seat 66 becomes expanded (partly gas and partly liquid). The expanded refrigerant is received in the conduit 42 at pressures somewhat greater than those normally existing in the expansion conduits. This high pressure expanded refrigerant leaves the injector and enters the liquid refrigerant in the conduit 42 where the pressure is somewhat lower. Consequently, the injector provides a means of positively circulating liquid refrigerant in the various refrigerant evaporators. It will also be noted that the gaseous part of the injected refrigerant immediately initiates the ebullition of refrigerant in the expansion conduits upon its admission thereto. Also the gaseous part of the injected refrigerant, in addition to starting the ebullition in the expansion conduits, promotes ebullition throughout its passage therethrough.

By positively circulating, initiating and promoting ebullition and the circulation of refrigerant, both liquid and gaseous, in the refrigerant evaporators, the oil pumped thereinto by the compressor is readily returned to the compressor through the vapor conduit 58, by reason of its entrainment with the evaporated refrigerant.

In the case of refrigerators utilizing a single cooling unit to cool a food compartment and to maintain ice cubes and desserts in a frozen condition, the users are frequently called upon to stop the compressor in order to allow the frost which accumulates on the surface of the cooling unit to melt. During this defrosting period the ice cubes and frozen desserts can no longer be maintained as such, occasioning much annoyance and inconvenience to the user of the refrigerator. To avoid this condition, it has been found desirable and also economical to install in the low side of a refrigerating apparatus more than one expansion coil, said coils being operable, if desired, at different temperatures.

In accordance with my invention, I provide for maintaining the evaporators 36 which may be considered as a single evaporator, and the shelf evaporator 40, either at the same temperature or at different temperatures, depending upon conditions within the refrigerator and upon the type of refrigeration required. This is accomplished by merely providing the manually operable valve 50 which is disposed at the juncture point of the two evaporators 36 and the conduit 52 opening into the top of the tank. This valve serves to control the amount of refrigerant which is circulated through the evaporators 36. Preferably, valve 50 is of the packless type. The flow of refrigerant through the expansion conduits 36 may be retarded to a predetermined amount or may be entirely shut off by means of this valve. When the flow of refrigerant is entirely stopped through said conduits no refrigeration will take place in the respective conduits. When the valve is operated to retard the flow of refrigerant through the evaporators 36, the refrigerating effect of said evaporators will be reduced and will be less than that of the evaporator which is provided with an unrestricted outlet passage, namely, the shelf evaporator 40. This valve is not of the pressure responsive type but is of the type which positively shuts off the flow of refrigerant through an expansion coil or permits a predetermined amount to flow through said coil without variation except when manually adjusted.

From the foregoing, it will readily be apparent that the retarding of the flow of refrigerant through some of the refrigerant evaporators will

decrease the amount of liquid refrigerant as well as the amount of gaseous refrigerant which is being circulated through an evaporator. By slowing up the circulation of refrigerant through the evaporators 36 and keeping the liquid level down, the rate of heat transfer has been lessened, which effects the heat transfer characteristics of the respective evaporators to maintain as a result a higher temperature in said evaporators than in the evaporator 40 in which the flow of refrigerant is unrestricted. It will also be noted that the refrigerant supply conduit 42 is in open communication with the inlet ends of each of the refrigerant expansion coils, and for this reason the pressures in the various expansion coils will normally be substantially equal. Furthermore, it will be noted that the temperatures of the various evaporators may be controlled by simply manipulating the valve 50.

During the on-phase of the refrigerating cycle, the condensing element withdraws evaporated refrigerant from the gaseous refrigerant space in the tank 34 into which the evaporators 36 and 40 expel refrigerant vapor produced within their own respective conduits. During this time it has been found that there is a slight pressure difference equal to only a few inches of liquid refrigerant pressure on opposite sides of the valve 50 when it is partly closed. This slight pressure difference causes a slight amount of liquid refrigerant in the expansion conduits 36 to be forced back into the conduit 42 to the tank 34. During the off phase of the refrigerating cycle and when the valve is but partly closed, the pressures on opposite sides of the valve are substantially, if not entirely, equal. Under these circumstances the level of liquid refrigerant in each of the expansion conduits and the tank 34 is the same. Preferably the level of liquid in tank 34 is above conduit 54 but below the outlet of conduit 52. The size of tank 34 is such that it will hold all of the liquid backed up from evaporators 36.

In order to arrange for ready access to the valve 50, I have provided a rod 70 (Fig. 3) attached to the valve 50 and extended through the front of the casing 27 at 86. A knob or handle 88 is fastened on the end of rod 70 outside the casing 27 to facilitate manipulation of said valve. This places the system in readiness for the selective control of temperatures.

During normal operation of the refrigerating apparatus, the coils 36 along the inside of the casing 27 which serve to cool the air circulating through the food compartment 24 and the shelf evaporator 40 which is adapted to maintain ice cubes and desserts in a frozen condition are kept at substantially the same temperature. In other words valve 50 is nearly or completely open. Liquid refrigerant flowing through the two expansion conduits 36 at substantially the same pressure not only serve to remove heat from the air contacting the outer surface of the metal casing 27 but also acts as a protective barrier to the shelf evaporator 40 in that the heat of the food compartment is prevented from penetrating as far as the surface of the evaporator 40, thus permitting the said expansion conduit to act exclusively to maintain the freezing compartment within the casing 27 at a predetermined low temperature. The casing 27 also prevents contact of circulating air with evaporator 40 so as to prevent the extraction of moisture from said air.

However, during periods of normal operation of the refrigerating apparatus, frost ordinarily col-

the contents of pans placed upon the shelves 46 in a frozen condition results during the period of defrosting the outer shell 27.

The collection of frost upon the outer surfaces of a refrigerant evaporator has hitherto been considered a disadvantage over which little or no control could be exercised. By means of my invention, however, it becomes possible not only to vary the amount of frost collected during normal operation of the refrigerating unit, but also to prevent its formation entirely. If the surfaces of the metal casing 27 be greatly increased and the coils 36 lining the inside of same be constructed in such a fashion as to permit only very little amount of refrigerant to circulate therethrough, no frost at all will collect or, if any, such a small amount that it will melt between 35 cycles of operation of the refrigerating unit. On the other hand, it may be desired to maintain the outer evaporators 36 below freezing at all times except when defrosting in which case, the surface of the shell 27 would be reduced and the 40 quantity of liquid refrigerant circulating through said evaporators increased. Thus it is apparent that great latitude in varying the conditions within the food compartment is afforded without altering the effectiveness of the shelf evaporator 45 40 in maintaining continuously a predetermined freezing temperature.

In Figure 6 of the drawings there is shown a form of valve structure 50 suitable for use in connection with refrigerating systems hereinbefore described. The valve structure 50 comprises, in general, a casing 90 having a bore 91 which serves as a chamber for fluid. The casing is also provided with two inlets, 92 and 93, and an outlet 94 for the passage of fluid to and from the chamber 91. Within the chamber 91 there is disposed for movement a valve proper 95 which cooperates with a valve seat 96 to control the passage of fluid through the chamber 91. To the valve proper there is joined, preferably integrally, a 60 push rod or actuator 97 for actuating the valve proper 95.

In order to provide a packless valve and one which is sealed against leakage of fluid from the chamber 91, I have provided flexible means which 65 permits operation of the valve proper from the exterior of the chamber 91 but which hermetically seals said chamber against leakage. This flexible means constitutes a flexible bellows 98. This bellows is sealed on one end thereof to a shoulder 99 of an annular sleeve 100, which is preferably press fitted into bore 91 to prevent the escape of fluid between the outer wall of sleeve 100 and bore 91. The opposite end of bellows 98 is sealed to an annular ring 101, which is preferably welded or soldered to the push rod

spring applies its force to an annular shoulder or ring 108 which is secured to push rod 97 by key 109 immediately above ring 101. When the valve is in a closed position, the spring is under compression so that the moving of threaded member 105 upwardly permits the valve and push rod to follow such upward movement to open the valve to the extent desired.

When the valve is in an open position, the turning of the threaded member 105 in a direction which causes it to move downwardly will cause the valve proper to move downwardly toward closing position, by reason of the fact that the end of said member is in engagement with the 30 push rod 97 at all times.

Although the valve structure above described is a preferred one, it is to be understood that other valves, well-known in the art, for example, valves of the electromagnetic type, may serve equally 35 as well for certain purposes as the one herein described.

In Figure 7 there is shown a modification of the refrigerating apparatus above described. The thermostat bulb 79, instead of being attached to 40 the side of the tank 34 is placed in good thermal contact with the outside of casing 27, so that the operation of the compressor is controlled in response to changes in temperature of the metal shell 27. This may be desirable under certain 45 conditions of operation.

In Figures 8 and 9 there is shown another modified form of refrigerating apparatus which comprises, in general, an insulated cabinet 114 having a compartment 116 in the top of the 50 cabinet, wherein a temperature below the freezing point of water may be maintained, and a compartment 118 wherein food is adapted to be stored. Within the compartment 116 there is disposed a tank 120, corresponding to tank 34 55 in Figures 2, 3, and 4, a shelf evaporator 122, which serves the same purpose as expansion conduit 40. In compartment 118 there is disposed an expansion conduit 124 in good thermal contact with a metal sheet 126. The conduit 124 60 corresponds to the evaporators 36 of Figures 2 and 4.

The structure of the above modified refrigerating apparatus is the same as that of the apparatus previously described; it differs only in 65 the location of parts within the cabinet. Liquid refrigerant is supplied to the evaporators 122 and 124, and tank 120 through a supply line 128 which terminates in an injector 130. The injector is in open communication with both evaporators and 70 with the interior of tank 120. Evaporator 124 communicates with the top of the tank 120 through a conduit 130; shelf evaporator 122 is always in open communication with the top of tank 120 through conduit 132. Refrigerant va- 75
